Primary Examiner — T. Chase Nelson*Assistant Examiner* — Eric Goodman*(74) Attorney, Agent, or Firm* — McHale & Slavin, P.A.(57) **CLAIM**

The ornamental design for a utility shed, as shown and described.

DESCRIPTION

FIG. 1 is a front right perspective view of the utility shed of the instant invention;

FIG. 2 is a front left perspective view thereof;

FIG. 3 is a front view thereof;

FIG. 4 is a rear view thereof;

FIG. 5 is a left side view thereof;

FIG. 6 is a right side view thereof; and,

FIG. 7 is a top view thereof.

The portions of the figures illustrated in broken lines are for illustrative purposes only and form no part of the claimed design.
